FIRE ALARM BOX

Nathan Verger, Brooklyn, N.Y., assignor, by mesne assignments, to Pittsburgh Railways Company, Pittsburgh, Pa., a corporation of Pennsylvania

Filed June 28, 1962, Ser. No. 70,726

Term of patent 14 years

(Cl. D72—1)

FIGURE 1 is a front elevational view of a fire alarm box showing my new design;

FIGURE 2 is a side elevational view of one side thereof, the oposing side being similar;

FIGURE 3 is a rear elevational view thereof;

FIGURE 4 is a top plan view thereof; and

FIGURE 5 is a bottom view thereof;

FIGURE 6 is a partial transverse sectional view taken on line 6—6 of FIGURE 1; and FIGURE 7 is a transverse sectional view taken on line 7—7 of FIGURE 1.

I claim:

The ornamental design for a fire alarm box, substantially as shown and described.
